UNITED STATES PATENT OFFICE.

PERCY WILFRED DODD, OF STAFFORD, ENGLAND.

SPRING-GRIP EXERCISER.

1,367,243.

Specification of Letters Patent.

Patented Feb. 1, 1921.

Application filed May 21, 1920. Serial No. 383,301.

To all whom it may concern:

Be it known that I, PERCY WILFRED Dodd, a subject of the King of England, residing at Stafford, England, have invented a new and useful Spring-Grip Exerciser, of which the following is a specification.

My invention relates to spring grip dumb-bells or exercisers for physical culture exercises and refers to dumb-bells or exercisers formed in two parts or halves guided or hinged with respect to each other and with a metal blade or bow spring or series of removable blades or springs interposed between them, permitting adjustment of the 10 resisting power to be effected.

An object of my invention is to provide an improved means of adjusting the resisting power of the bow or blade spring dumb-bell or exerciser to compression by the grip 20 of the hand to suit different users, and to facilitate insertion and location of the springs therein.

The invention is applicable to a metal dumb-bell to provide weight in addition to the grip or to a light grip exerciser of wood or other suitable substance, or the parts of the dumb-bell or exerciser may be formed as metal pressings.

In my invention, I employ for the spring 30 a number of spring leaves or plates adapted to nest together and having means for locating them in relation to each other and to the rigid parts of the dumb-bell or exerciser. For this purpose each spring leaf or plate 35 has a depression on one side forming a nib or projection on the other and one part of the dumb-bell or exerciser has a depression with an entrance groove leading to it to facilitate insertion of the spring leaves. Be- 40 yond the depression in the dumb-bell part is a stop which may conveniently be formed as a projecting lug or nib.

There may be more than one depression in the spring plates and in the dumb-bell part 45 if desired but I prefer one central depression which corresponds to the central part of each bow spring.

In order that the invention may be easily understood I have illustrated two examples 50 of construction in the appended drawings:

Figure 1 is an elevation of a dumb-bell with my invention applied.

Fig. 2 is a sectional view thereof.

Fig. 3 is a central cross section thereof.

Fig. 4 is a sectional plan showing the inner face of one part of the bell.

Fig. 5 is a plan of one half of a pressed metal bell.

Fig. 6 is a similar view of the other half.

Fig. 7 is a central vertical section of a 60 pressed metal dumb-bell complete with spring.

In the example shown at Figs. 1 to 4 the two parts *a* and *b* of the dumb-bell are solid and may be conveniently formed by casting. Suitable guide pins are indicated at *c*. In my improvements the one half *b* has a central depression *d* and preferably a shallow groove *e* leading to it from one side of the handle portion. At the other side of 70 this portion beyond the depression *d* is formed an abutment or stop *f*.

The main leaf or plate *g* of the spring is shown in the example of single bow form with slightly lipped ends *h*, and at its central part has a pressed nib *i* adapted to be engaged in the depression *d* in the half *b* of the dumb-bell. The lipped ends *h* bear against the other half *a* of the dumb-bell and the spring may be readily pressed in between the two halves by the fingers of the user; the stop *f* locating the leaf in correct position. For the other leaves *j* similar plates are employed but the lipped parts may be omitted, and if desired the other 85 plates may be graduated in length like the laminæ of a laminated spring. Each leaf may be readily inserted below the main leaf and the nibs *i* nest together and engage the bell as clearly shown at Figs. 2 and 3. 90

A light pressed metal construction, as shown at Figs. 5 to 7 may be produced as two shell-like pressings. Bearing plates or platforms *k* at the ends of one half *a* and a central plate or platform *m* on the other half *b* may be secured to the shells or formed as integral extensions of the blank from which each shell is pressed.

For the parts *k* the extensions may take approximately the form indicated in dotted 100 lines at Fig. 6, assuming the dumb-bell halves to have semi-hexagonal ends. The portion *n* may then be folded up vertically to close the end of the bell and the part *k* folded again into horizontal position to rest 105 on the sides of the shell and form the platform for the spring ends *h* to bear against.

The central extension for the platform *m* on the half *b* may be as shown in dotted lines at Fig. 5 and may be folded over into the 110 position shown in full lines. The depression *d* and groove *e* may be pressed in the

extension and a stop *f* may be riveted or otherwise secured thereto or formed as a corrugation in the pressings.

To guide these pressed half bells I may 5 slot the platforms *k* as at *o* and insert the cranked ends of guide pieces *p* therein and then raise the guides into vertical position and rivet or bolt them to the other half *b* as shown at Fig. 7.

10 I claim;—

1. A spring grip exerciser comprising in combination two rigid grip members, guiding and connecting means between said rigid members, and a laminated spring disposed 15 between said rigid members tending to separate said members to the limit of said connecting means, said spring consisting of removable leaves with means for nesting said leaves together, and means comprising a recess and stop on one of said rigid members for locating said spring readily in said members.

2. A spring grip exerciser comprising in combination rigid grip members, means for 25 connecting said members said means permitting movement between the members and guiding them during such movement, resilient means interposed between said members, said resilient means consisting of a 30 spring made up of removable leaves having coengaging projections and recesses between them; a locating recess on one member a stop adjacent thereto and entrance means so that the projections of the leaves may enter 35 said recess in said member to locate the spring between the members.

3. A spring grip exerciser with a laminated spring between the parts thereof, a plurality of removable bow shaped leaves comprising said spring, a depression in one 40 face of each leaf causing a projection on the opposite face, said depressions in the leaves being coincidentally formed so that said leaves nest together, a corresponding recess in the inner face of one of said parts of the 45 dumb-bell a projecting abutment on one side of said recess and an entrance groove on the other side of said recess.

4. A spring grip exerciser formed of two 50 hollow pressings, rigid platforms over the central part of one of said hollow pressings and rigid platforms over the end parts of the other; connecting and guiding means between said two pressings, and a leaf spring 55 with removable leaves located between said pressings and engaging said rigid platforms.

5. A spring grip exerciser formed of two hollow pressings, a rigid platform formed over the central part of one of said pressings, and rigid platforms over the end parts of 60 the other of a depression with an entrance groove and an adjacent abutment on said central platform; connecting and guiding means between said pressings and a leaf spring 65 with removable leaves between said pressings, said leaves having coöperating recesses and projections to engage each other and to engage said central platforms, and one of said leaves having curled ends to rest upon said end platforms.

PERCY WILFRED DODD.
